(57) **CLAIM**

The ornamental design for a bolt extractor, as shown and described.

DESCRIPTION

FIG. 1 is a perspective view of a bolt extractor embodying our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines of the bolt extractor in FIGS. 1-7 are illustrative of portions of the bolt extractor that form no part of the claimed design.
